UNITED STATES PATENT OFFICE.

THATCHER W. WALKER, OF COLGATE, MARYLAND, ASSIGNOR TO THE BARTLETT HAYWARD COMPANY, OF BALTIMORE, MARYLAND, A CORPORATION OF MARYLAND.

FIRING DEVICE FOR PROJECTILES.

Application filed August 8, 1917. Serial No. 185,012.

To all whom it may concern:

Be it known that I, THATCHER W. WALKER, a citizen of the United States, residing at Colgate, in the county of Baltimore and 5 State of Maryland, have invented certain new and useful Improvements in Firing Devices for Projectiles, of which the following is a specification.

This invention relates to an improved impact firing device for projectiles or shells.

One object of the invention is to provide an improved construction of firing device that will be simple in construction, avoid the use of a firing pin that is movable with respect to the body that carries it to put it into an armed condition; that will dispense with shear devices, and which will operate only upon rotation of the shell and during the action of centrifugal force.

One embodiment of the invention is 20 illustrated in the accompanying drawing wherein,—

Fig. 1, shows a longitudinal sectional view through a fuse-body or case in the chamber of which the improved firing device is located.

Figs. 2 and 3, illustrate the detached firing device in side elevation,—one view being taken in a direction at a right angle with 30 respect to the other.

Fig. 4, shows the detached firing device in top plan.

Fig. 5, illustrates a vertical sectional detail through the device as the same would 35 appear if cut on the line 5—5 of Fig. 2.

Fig. 6, shows another sectional detail through the device,—the section being taken on the line 6—6 of Fig. 3.

Fig. 7, illustrates the detached firing-pin 40 bar in side elevation.

Fig. 8 shows a sectional view through the firing device with the parts in the firing position and

Fig. 9, illustrates the same in side elevation.

In the present disclosure of the invention, the improved firing device or plunger is shown as contained in the chamber *a*, of a fuse or stock body *b*,—a simple form of 50 such stock being shown in Fig. 1, of the drawing for illustrative purposes only, but the invention is in no way to be limited to the design or construction of the stock shown.

In the present instance the stock has a cir-

cumferentially-threaded wall *C*, by means of which it may be attached in the base of a shell, and at its inner end has a primer cap *d*, which will be fired upon impact, to 60 explode the main charge in the shell.

It is to be understood however that the improved firing device may be located in a fuse-body at the nose-end of a shell, in which case, the body containing the device, will be varied in design to meet the conditions caused by such change in location.

The improved device in the present instance, has a body 12, which is shaped exteriorly to conform to the shape of the chamber *a*, of the fuse stock so as to maintain it against lateral movement in said chamber but, under conditions presently to be explained, permit certain of its parts to have a longitudinal movement in the 70 said chamber.

In the present instance the chamber *a*, and the firing device body are circular, and the latter is sufficiently smaller in diameter to enable it to have free longitudinal movement in the chamber as, and for a purpose 80 presently to be explained.

The body 12, is provided with a vertical slot 13, which extends diametrically therein and crosswise from one side to the other of the body. This slot opens at the upper 85 side of the body but terminates short of the lower side whereby to leave a thickness of metal at 14, across the body and below the slot.

At the lower end of the slot the body is 90 provided, in this instance, with two circular cavities 15, in which the lower ends of comparatively light coiled springs 16, are seated. The opposite side walls of the slot 13, from the base of the slot upwardly, are provided 95 with segmental cut-outs 17, so that a plunger-head 18, may be seated on top of each spring and be held against lateral displacement by having its diametrically opposite sides guided in the said cut-outs 17. The 100 plunger-heads 18, are therefore yieldingly sustained in the slot and are capable of vertical movement therein.

At the upper side, the body 12, is provided with a central upwardly-projecting firing pin 19, which is rigid with and has no movement independently of the body.

The precise form and arrangement of this pin is not essential to the invention, but in the present instance, it is formed on, or 110

carried by a rigid bar 20, which extends diametrically across, and is secured in, a groove in the upper side of the body. This bar, as seen in Figs. 4, 5 and 6, of the drawings, bridges the upper side of the slot 13, and closes said slot at a central point and beneath the firing pin 19.

A locking bar 21, is carried by the body and has its lower portion extending down into the slot 13. This locking bar has a vertical slot 22, at its upper side which straddles the bar, 20, and the firing pin 19, and the base wall 23, of the slot seats against the under side of the firing pin or the bar 15 which carries that pin, as clearly shown in Fig. 6.

The under side of the locking bar is shaped so as to produce two side ledges 24, and a central ledge 25,—the side ledges extending over and being seated upon the upper sides of the two plunger heads 18, whereby the locking bar will be yieldingly held up with the base wall 23, of the central slot 22, seating under the rigid bar which forms 25 a stop and limits the outward movement of the bar with respect to the slot 13.

It will be noted that the normal position of the locking bar 21, is such that its outer or upper edge 26, has position beyond 30 the end of the firing pin 19, and that the latter has a depressed position in the slot 22, of the locking bar where it is retained in a safety condition.

Below the central ledge 25, of the locking 35 bar the body 12, of the device is provided with two crosswise passages 27, extending in a direction at right angles to the slot 13, and whose inner ends are in alignment and open at opposite sides of said slot, as shown 40 in Fig. 5, of the drawing.

Each of these passages 27, communicates at its outer end with a smaller passage 28, so that a guide stem 29, may be located in each passage with its outer end guided in 45 the smaller passage and its inner end connected to a bolt head 30, which latter can slide in the larger passage 27.

Light coiled springs 31, are confined in the larger passages and around the guide 50 stems 29, so as to press the stems and bolt heads 30, toward the center of the detonator body.

By reference to Fig. 5, it will be seen that the two bolt heads 30, are normally located 55 directly under the central ledge 25, of the locking bar and are exposed to the interior of the vertical slot 13, so as to prevent a telescoping movement of the locking bar and body, and therefore, as long as the bolt heads are in this normal position, the body and locking bar cannot move, one toward the other, which is necessary to expose the firing pin for operation.

In practice, the device is placed in the 65 chamber *a*, of the fuse stock with the edge 26,

of the locking bar seated against the under side of the plug *e*, which carries the primer, and with the bottom of the body seated against the outer wall, *f*, of the stock chamber, as shown in Fig. 1. In this safety position the locking bar is held projected from the slot of the plunger body and the firing pin 19, has a depressed position in the slot 22, of the locking bar and cannot move forward toward the primer *d*, because the bolt heads 30, keep the body and locking bar separated, as shown in Fig. 5.

When the parts are therefore in the position shown in Figs. 1 and 5, they are locked, in what is termed the safety or unarmed condition; and accidental jars or shocks cannot shift the parts to an armed condition because of the bolt heads 30. It will be noted that the device entirely avoids the use of shear pins to hold the device in 85 a safety condition, and therefore the degree of shock to which a shell might be subjected has nothing to do with the liability of the device becoming armed.

The arming of the improved device 90 depends upon the centrifugal forces, due to the rotation of the shell in flight as will now be explained.

Figs. 8 and 9, of the drawing show sectional and side elevations respectively, of 95 the firing device with the parts in the armed position, or the position they assume at the moment of impact of the shell.

When the shell is fired, the firing device parts in the fuse stock will have the position shown in Fig. 1, and as the shell leaves the gun the rifling in the latter will impart a rotation to it, so that during flight, the shell is rotated at a comparatively high speed.

The centrifugal forces, due to the rotation of the shell, cause the stems 29, and the bolt-heads 30, to move radially in the body-passages 27, and against the action of the light springs 31, thereby moving the bolt-heads in 110 opposite directions, and from beneath the central ledge 25, of the locking bar. These bolt-heads are maintained in the retracted condition throughout the rotation and flight of the shell but the body 12, is held in its 115 rearward position in the chamber *f*, by the action of the springs 16, so that the firing-pin on the body will not move to strike the primer *a*, and effect an explosion, until the projectile itself strikes an object.

It will be understood that the firing pin has no movement independent of the body but moves only when the body moves, and therefore failure to arm is practically eliminated. It will further be seen that by avoiding all manner of shear devices to keep the device from arming, that accidental arming caused by jolts or jars is also eliminated.

By means of this invention the parts are locked in a safety condition; are unlocked 130

only by centrifugal force during flight, and then have practically no further movement until impact of the projectile takes place.

If for any reason, the projectile be subjected to a rotary motion that would cause the locking bolts to free the locking bar and thus put the parts in condition to arm, they will immediately return to a safety condition as soon as the rotary motion ceases or falls below the speed at which the device is designed to operate.

Having described my invention what I claim is,—

1. A firing device for projectiles having in combination a body, a central firing pin rigid with and projecting in advance of the body, means normally projecting from the body at opposite sides and in advance of the firing pin, yielding means on the interior of the body between the inner part of the projecting means and the inner part of the said body for keeping the projecting means extended, and centrifugally-operated locking means for normally holding the projecting means extended beyond the body and said rigid firing pin.

2. A firing device for projectiles having in combination a fuse stock provided with a chamber, a plunger body in said chamber and provided with a longitudinal cross-slot opening at the outer end thereof, a firing pin rigid with and projecting from the body, means extending longitudinally of and seated in the body-slot and projecting from one end thereof and in advance of the rigid firing pin to prevent forward movement of the plunger body in said chamber, and locking means located within the body and engaging the rear of the projecting means to normally maintain the projecting means in the extended position.

3. A firing device for projectiles having in combination a body provided with a diametrically-extending slot, a firing pin rigid with the body, a bar entering the slot said bar being slotted and projecting therefrom at opposite sides of the firing pin and in advance of the latter and locking means engaging the bar to prevent movement between the bar and body.

4. A firing device for projectiles having in combination a circular body provided with a diametrically-extending slot, a firing pin rigid with the said body and projecting centrally therefrom, a vertical locking bar seated in the body-slot said bar being slotted and projecting therefrom in advance of the rigid firing pin and at opposite sides of the latter, and a centrifugally-releasable locking bolt between the bar and body to prevent movement of one toward the other.

5. A firing device for projectiles having in combination a circular body provided with a diametrically-extending slot, a firing pin rigid with and projecting centrally

from the said body, a vertical locking bar seated in the body-slot said bar being slotted and projecting therefrom in advance and at opposite sides of the rigid firing pin, longitudinally yielding means interposed between the bar and body and tending to press the body and bar vertically from each other, and a centrifugally-releasable locking bolt between the bar and body.

6. A firing device for projectiles having in combination a circular body provided with a vertical cross-slot, a firing pin rigid with and projecting centrally from the body, a vertical locking bar seated in the slot said bar being slotted and projecting vertically therefrom at opposite sides and in advance of the rigid firing pin and centrifugally-releasable locking means carried by the body and engaging the inner edge of the vertical bar to prevent movement of the body with respect to the bar.

7. A firing device for projectiles having in combination a circular body provided with a vertical cross-slot, a firing pin rigid with and projecting centrally from the body, a vertical locking bar seated in the slot said bar being slotted and projecting vertically therefrom at opposite sides and in advance of the rigid firing pin, vertically yielding means in the slot for pressing the body in a direction away from the bar and locking means also in the slot between the body and bar to prevent movement of the body and rigid pin with respect to the locking bar.

8. A firing device for projectiles having in combination a body provided with a cross-slot, a firing pin projecting from the body, a locking bar seated in the slot of the body and slotted to straddle and project in advance of the firing pin, yielding means carried by the body and engaging the locking bar to exert a pressure on the body in a direction away from the bar and retain the firing pin in the slot of the locking bar, and centrifugally-releasable locking means to normally prevent movement of the body toward the bar.

9. A firing device for projectiles having in combination a body provided with a cross-slot, a firing pin projecting from the body, a locking bar seated in the cross slot, said bar being slotted and projecting at opposite sides of the firing pin said bar having side and central inner ledges, yielding means engaging the side ledges of the bar and pressing the body in a direction away from the bar, and a locking bolt carried by the body and engaging the central ledge of the locking bar.

In testimony whereof I affix my signature in the presence of two witnesses.
